GYMNASTICATOR

Arthur C. Hanson, Davenport, Iowa

Application April 2, 1945, Serial No. 586,258

5 Claims. (Cl. 73—11)

(Granted under the act of March 3, 1883, as amended April 30, 1928; 370 O. G. 757)

1

The invention described herein may be manufactured and used by or for the Government for governmental purposes, without the payment to me of any royalty thereon.

The present invention relates generally to apparatus for testing and/or exercising mechanisms prior to their installation in the assemblies in which they are intended to function or prior to their release for work and constitutes a continuation-in-part of my copending application entitled "Hydraulic Gymnasticator" Serial No. 415,248, filed October 16, 1941, now abandoned.

More specifically it concerns itself with that type of apparatus which has come to be known to the art as a "gymnasticator."

In devices of the type herein contemplated, those heretofore known have not, to my knowledge, been adapted to produce in the particular mechanism being exercised the exact cycle of operation which that mechanism will execute when at work in the capacity for which it is intended. Rather, previously known gymnasticators have in the main operated the mechanism being gymnasticated according to their own set and predetermined cycles. I have found that the purpose of a gymnasticator is served much more effectively and efficiently if it is so constructed as to be adapted to produce in the mechanism which it is currently gymnasticating a cycle of operation similar to that which the said mechanism will execute when actually at work.

Means for gymnasticating artillery recoil mechanisms have been my chief concern and I have found that by providing a device adapted to impart to a given recoil mechanism movements which are of substantially the same velocity and intensity as those which will be imparted to it when the gun which it is to carry is fired, I am able not only to determine in a general way that all parts are operable and intact but I am able to determine whether or not the particular mechanism is within tolerances in all respects and whether it is capable of withstanding the stresses to which it will be subjected when in use in the field, thus avoiding the necessity for proof firing.

It is therefore an object of this invention to provide a gymnasticator which is adapted to impart to the mechanism which it is designed to exercise and test movements similar in substantially all particulars to those which said mechanism will execute when at work in the capacity for which it was produced.

A more specific object of this invention is to

2

provide a gymnasticator adapted to produce in artillery recoil mechanisms a cycle of operation similar to that which said recoil mechanisms will carry out when attached to and used with artillery pieces.

A further object of this invention is to provide a gymnasticator which is adapted to impart motion through fluid means to the mechanism which it is gymnasticating.

10 Other objects of my invention will become apparent as this disclosure proceeds and include the provision of novel gymnasticator structure.

In general my invention in its preferred form comprises means for building up a fluid pressure head, means for rapidly releasing the pressure in said head and directing it into a mechanism which is to be gymnasticated, and means for timing the continuance of the subjecting of said mechanism to the pressure from said pressure head. Also preferably included is means for releasing the pressure built up in the mechanism as a result of its having been in communication with said pressure head.

15 In order to make a clear and concise explanation of my invention, I have accompanied this specification with drawings which form a part hereof and in which:

Fig. 1 is a side elevational view of a preferred embodiment of my invention, many parts being represented schematically;

20 Fig. 2 is a vertical sectional view of a preferred form of pressure switch employed in the assembly shown in Fig. 1;

Fig. 3 is a view similar to Fig. 1 and showing a modified form of my invention; and

25 Fig. 4 is a vertical sectional view of a pressure release valve employed in both of the embodiments of my invention disclosed herein taken on line 4—4 of Fig. 1.

30 As previously indicated, I have chosen to describe my invention in conjunction with the recoil mechanism of an artillery piece and as a gymnasticator for such a recoil mechanism. One of the outstanding characteristics of the action 35 of such a recoil mechanism when in operation as a part of a firing artillery piece is its extremely rapid and forcible initial recoil. This initial recoil is followed by continuing recoil movement of a gradually decreasing intensity and speed.

40 When the end of the recoil stroke has been reached the counterrecoil phase of the cycle commences and includes, again, a relatively rapid and forcible initial movement followed by motion in the same direction but of gradually decreasing intensity and speed until the mecha-

nism has returned to its initial or battery position. The initial movement in counterrecoil is, of course, not comparable in speed or intensity to the corresponding motion in the recoil phase.

I have provided an accumulator 10 in which I build up a very substantial fluid pressure by means such as a rotary pump 11 (Fig. 1) or a triplex piston pump 12 (Fig. 3). As shown in both assemblies of the drawing, the fluid under pressure in the accumulator is introduced through suitable conduit and valve structure into an artillery piece recoil mechanism, such a mechanism being shown fragmentarily at 13 in the drawing and including a piston 14, a cylinder 15, and a counterrecoil cylinder 16.

As shown in Fig. 1 particularly, the accumulator 10 is connected to a dry nitrogen source such as a conventional pressure storage tank 17 through a conduit 18 having adjacent the accumulator a shut-off valve 19 for disconnecting the tank 17 from the accumulator after nitrogen has been introduced into the accumulator. It will, of course, be clear that any inert or other suitable gas may be employed instead of nitrogen. The pump 11 takes oil from a reservoir 46 and forces it to the accumulator 10 through conduit structure 20. The pump is actuated by a motor or other suitable power source 21. Included in the conduit 20 is a pressure relief valve 22 and a check or one-way valve 23. A pressure-operated, piston type switch 24 is in communication with accumulator 10 and is thus responsive to the pressure within conduit 20. This switch 24 may be located anywhere between valve 23, the accumulator 10, and hydraulic valve 27, subsequently described. Connecting the accumulator with the recoil mechanism 13 is other conduit structure 25 which may, if desired, communicate with the accumulator 10 through a means common with the conduit 20 such, for example, as a pipe 26. Interposed in the conduit 25 is a quick acting, solenoid-operated hydraulic valve 27, the purpose and functioning of which will be made more clear hereinafter. Also connected to the conduit structure 25 at a juncture point between the valve 27 and the recoil mechanism 13 is a pressure release valve 28 which is interposed in a return conduit 29, the latter being directly connected to the conduit 25 at one end and communicating with reservoir 46 at its other end. The details of release valve 28 are particularly illustrated in Fig. 4. It will be noted that one end of conduit 25 connects directly into the cylinder 15 of the recoil mechanism through suitable fittings.

In order to cause the particular gun recoil mechanism with which I have been mainly concerned to execute a cycle of operation comparable to that which it will execute when in use in the field, it has been necessary, by way of example, to have a pressure of approximately 2500 pounds in the accumulator 10 at the time said accumulator is placed in fluid communication with the recoil mechanism for the purpose of gymnasticating the latter. In this particular set-up the quantity of oil required per minute is approximately two and one-half gallons.

To insure that the valve 27 and the valve 28 will always be in the desired relative positions, namely, the one open when the other is closed, I have connected a control rod 30 of the valve 27 to a control rod 31 of the valve 28 through a suitable lever and linkage such as 32. Also operatively connected to the control rod 30 of

valve 27 is the plunger of a solenoid 33 adapted to open said valve when energized. A spring 34 is provided for maintaining the valve 27 in a normally closed position and its size is such as enable it, through the linkage 32 and control arm 31, to operate the valve 28 for maintaining the latter in a normally open position. In order to render the solenoid 33 and hence the operation of the valve 27 responsive to the pressure within the accumulator 10, the pressure switch 24 is operatively connected as previously described. In the particular arrangement disclosed in Fig. 1 a combination transformer and rectifier 35 of conventional design is connected into the electrical circuit including lines 36 and the switch 24 to transform the 110-volt 60-cycle alternating current of lines 37 into 6-volt direct current. Also connected into the circuit including the conduits 36 and the switch 24 is a condenser 38, a variable resistance 39, and a supersensitive relay 40. The contact points of the supersensitive relay 40 are connected into an electrical circuit which includes a power relay 41 and those of the power relay 41 are connected into the electrical circuit including conduits 42 which supplies the solenoid 33. Thus when adequate pressure has been built up in the accumulator 10 by the pump 11, say, for example, 2500 p. s. i., the switch 24, being set to operate at this predetermined pressure, closes contacts 43 and 44, causing the supersensitive relay 40 to energize the power relay 41 which in turn causes operation of the solenoid 33 thus opening valve 27 and closing valve 28. By this operation the fluid in accumulator 10 which has been stored at very high pressure is suddenly permitted to act against the piston 14 of the recoil mechanism 13 causing the same to travel in recoil at an intensity and speed comparable with that of actual operation. In the particular assembly which I have shown, the contacts 43 and 44 are broken substantially immediately after the initial pressure drop in the accumulator 10 due to retraction of a plunger 45 in the switch 24. However, the valve 27 is not immediately closed and the valve 28 opened as a result of action of the spring 34, since the condenser 38 continues to discharge thereby energizing the supersensitive relay 40 for a predetermined time after the breaking of the contacts 43 and 44, said predetermined time being variable by adjustment of the resistance 39. The period of recoil of the particular mechanism 13 being approximately three-quarters of a second, the resistance 39, in the assembly herein illustrated, is so set that the contacts of the supersensitive relay 40 will be retained closed for approximately three-quarters of a second as a result of the combined action of the closing of the contacts 43 and 44 and of the condenser 38. The pressure in the accumulator being somewhat less after the initial discharge and gradually decreasing as the valve 27 continues to remain open, the desired action of the piston 14 moving gradually slower and with less intensity in recoil after the initial movement is afforded.

The mechanism 13 having been thus placed in recoil position, counterrecoil action is afforded by the compressed nitrogen in the counterrecoil or recuperator chamber 16 in the same manner as when the mechanism is attached to a firing gun. This action is permitted, since the condenser 38 ceases to energize the supersensitive relay 40 at approximately the same time the end of the recoil stroke of the mechanism is reached.

The valve 27 is closed and the valve 28 is opened at that time as a result of the action of the spring 34 so that the oil which has been forced into the chamber 15 by the accumulator is free to discharge therefrom out through a portion of the conduit 25 and then through the conduit 29 and the valve 28 to the oil reservoir 46 from whence it returns to the sump of the pump 11. When the accumulator has again reached the predetermined pressure, the operation is repeated.

A gage 47 is shown as connected to the recuperator chamber 16 of the mechanism for indicating the pressure therein and a gage 48 is shown as connected to the accumulator for indicating its pressure. A valve 49 and a conduit 50 are provided for draining the accumulator when desired.

In Fig. 2, which comprises a detailed showing of the pressure switch 24, a cylinder 51 receives the head of the piston 45, the shank or rod 52 of which is received in a smaller cylinder 53 which is connected through suitable conduit structure 54 to the accumulator 10. A heavy spring 55 serves to hold the piston 45 in a normally depressed condition. Electrical contacts 43 and 44 are mounted in a plug 56 inserted in a piston cap 57 and are preferably longitudinally slideable in said plug 56 within limits. Springs 58 and 59 which are also electrical conductors are adapted to retain said contacts in predetermined normal positions and to connect them with conductors 36. A bar 60 on the face of the piston 45 is an electrical conductor adapted to close contacts 43 and 44 when piston 45 has been forced upwardly in cylinder 51, as a result of pressure in the accumulator 10, to a point such that said bar 60 is in engagement with contacts 43 and 44.

In the modified embodiment shown in Fig. 3, a large number of the components are the same as in Fig. 1 as will be apparent from corresponding reference characters. However, I have disclosed certain refinements which may be desirable in some assemblies. For example, a bellows type pressure switch 61 mounted, in this instance, on the top of the accumulator 10, replaces the pressure switch 24 and is provided with a plurality of simultaneously operable contact makers 62 and 63. The contact maker 62 is adapted to close the circuit including a power source 64, a resistance 65, and a solenoid 66 which has a plunger 67 carrying a contact maker 68 adapted to close another circuit which includes the solenoid 33. The contact maker 68 is insulated from the plunger 67 by any suitable means 69 and a short-circuited copper ring 70 is provided adjacent one end of the solenoid 66 but spaced therefrom by a suitable nonmetallic shim 71 for maintaining a magnetic field adapted to hold the plunger 67 in retracted position for a predetermined time after the circuit maker 62 ceases to close the circuit which includes the solenoid 66, whereby the circuit maker 68 is maintained in operative position for an extended time and the solenoid 33 continues to be energized. The resistance 65 enables variation in the effective period of the copper ring 70. A hand switch 72 is provided for optionally cutting out the circuit maker 68 and another hand switch 73 is provided for enabling manual control of the energizing of the solenoid 33. Circuit maker 63 is also adapted to close a circuit which includes a power source 74, a resistance 75, and a solenoid 76. The solenoid 76 is provided with a plunger 77 operatively connected to a circuit breaker 78 through insulation 79. The circuit

breaker 78 normally closes the circuit of the motor 21 which drives the pump 12 and closure of the circuit maker 63 causes retraction of a plunger 77 resulting in the circuit breaker 78 breaking the pump motor circuit, whereby the supplying of additional oil to the accumulator during the operation of the recoil mechanism 13 by the accumulator is averted. A short-circuited copper ring 80 is provided for delaying the return of the circuit breaker 78 to contact position and the adjustment of the resistance 75 is preferably such that the time delay effected by the ring 80 is substantially equal to that effected by the ring 70.

In exercising the particular recoil mechanism heretofore referred to I have found it expedient to regulate my gymnasticator in such manner that the drop in pressure in the accumulator does not exceed approximately four percent. Also, in order to make the action more nearly conform to that of the mechanism when a firing artillery piece is attached, in addition to regulating to three-quarters of a second the time during which the valve 27 is open and the accumulator is in communication with cylinder 15 of the recoil mechanism, I have adjusted my device so that the period during which the valve 27 remains closed, (in other words the period from the end of one recoil movement to the commencement of the next recoil movement), is approximately twenty seconds. Such adjustments may vary even for a particular type of mechanism and will necessarily vary with the different types of mechanisms being gymnasticated. If desired, a conventional floating piston or suitable substitute may be inserted in the accumulator 10 between the gas and the liquid.

My novel process for exercising a mechanism comprises, in its preferred form, the building up of a fluid pressure adequate to accomplish the actuation of the particular mechanism involved in accordance with the normal cycle of said mechanism and subsequently introducing said fluid into the said mechanism whereby said mechanism is caused to execute said cycle. Usually but not invariably my process will be accompanied by a further step, namely, that of causing or permitting, as the case may be, said fluid to mainly discharge from said mechanism. In instances such, for example, as that of recoil mechanisms, where the mechanism being exercised has a static or normal position, it is, of course, necessary to supply energy for duplicating only that portion of the cycle of said mechanism which places it in maximum unstable position, after which the outside force being applied will normally be removed or released permitting the unit to return to equilibrium of its own accord.

It is not positively essential to my process that the energy be accumulated into a head before being applied to the mechanism being gymnasticated; instead, if equipment of adequate size, power, and, if necessary, variability is available it may be used to drive the mechanism directly. If the energy is accumulated it need not necessarily be in the form of fluid under pressure and while, as previously indicated, I distinctly prefer to introduce fluid directly into the mechanism being gymnasticated, it is possible to execute my process of artificially duplicating in a mechanism the cycle of operation which it will perform when at work by mechanically connecting said mechanism to a suitable gymnasticating means.

My novel process and exercising apparatus have a number of advantages in addition to the factor

of convenience in being able to test and/or exercise a mechanism, such, for example, as the recoil mechanism of a gun, without the necessity for transporting it to a proving ground and thereby subjecting it to proof firing. Among these other advantages is included the factor of economy. For example, the cost of gymnasticating a weapon with my gymnasticator is approximately one twenty-fifth of the cost of actual firing of the weapon. Also, of great importance when the mechanism being tested is one which is in the development stage, my apparatus and process enable convenient observation of its functioning and parts including, when necessary, adaptation of the testing operations to a permanent high-speed motion picture photographing set-up.

As previously indicated, both my novel process and my unique gymnasticator may be employed in the exercising and/or testing of various mechanical structures and need not be strictly limited to gun recoil mechanisms.

In addition to adaptations necessary to accommodate my gymnasticator to the particular mechanism to be exercised, a great many modifications, substitutions, and eliminations may be made therein. For example, while it preferably includes some means for applying fluid at varying pressures to the mechanism being gymnasticated, it may incorporate structure for otherwise applying power adapted to propel said mechanism according to the predetermined cycle which it is intended to execute after being placed at work. Of course, proper execution of the cycles of certain types of mechanical structures will require uniform rather than varying power application and such is obviously contemplated by my invention, it being permissible to adapt my gymnasticator thereto. Power variations, when necessary to properly execute the cycle of a particular mechanism, may be provided either by the power source or by suitable regulation of the means connecting the said power source to the mechanism.

While I have described specific embodiments of my gymnasticator and process of gymnastication for illustrative purposes, it is clear that numerous modifications, alterations, and eliminations may be made therein by one skilled in the art without departing from the spirit and scope of my invention.

I claim:

1. For use with a machine element having a predetermined cycle of operation, hydraulic means for actuating the element to simulate its normal cycle of operation comprising a fluid pump, an accumulator for the fluid pumped, a normally closed solenoid valve connected between the accumulator and the element, an electric switch responsive to pressure in the accumulator, electric means including the pressure responsive switch constructed and arranged to recurrently open the solenoid valve in consonance with the initial time unit of the said cycle, a return circuit for said fluid from the element, a valve in said circuit and a connection between said valve and said solenoid valve whereby the one is open when the other is closed.

2. For use with an element having a predetermined cycle of operation, hydraulic means for actuating the element to simulate its normal cycle of operation comprising a fluid pump, an accumulator for the fluid pumped, a normally closed

solenoid valve connected between the accumulator and the element, an electric switch responsive to pressure in the accumulator, a second electric switch closed by closure of said first switch and having a time element, a third electric switch opened by closure of said first switch and having a time element, said second switch controlling current through said solenoid valve such that it remains open during the initial time unit of said cycle of said member, and said third switch controlling said pump such that fluid is stored during the final time unit of said cycle.

3. In a hydraulic means as in claim 2, a return circuit for said fluid, a valve in said circuit and a connection between said latter valve and said solenoid valve whereby the one is open when the other is closed.

4. In an apparatus for testing the operation of a hydraulic pressure operated recoil mechanism for guns, an accumulator, fluid pressure means connected and operable to increase the pressure in said accumulator, a supply conduit connected at its first end with said accumulator and adapted for connection with said mechanism at its second end, a first, normally-closed, quick acting valve in said conduit, an exhaust conduit communicating with said supply conduit between said first valve and said second end of said conduit, a normally-open second valve in said exhaust conduit, operating connections between said valves whereby one is open when the other is closed, spring means urging said first valve to open position, a solenoid having an armature connected to open said first valve and close said second valve when said solenoid is energized, a switch responsive to pressure in said accumulator, and circuit means including said switch, solenoid and a source of potential and operative to momentarily energize said solenoid on increase in pressure in said accumulator to a definite value, to thereby open said first valve and to close said second valve.

5. The apparatus as specified in claim 4, said fluid pressure means comprising a compressor and a motor connected to drive the same, a supply circuit for said motor including a relay switch, and means operated by said pressure responsive switch to open said relay switch on attainment of said definite pressure value.

ARTHUR C. HANSON.
